Primary Examiner — Garth Rademaker*Assistant Examiner* — Melanie Pellegrini(74) *Attorney, Agent, or Firm* — Dickstein Shapiro LLP**CLAIM**

The ornamental design for jewelry, as shown and described.

DESCRIPTION

FIG. 1 is a perspective view of jewelry showing my new design;

FIG. 2 is a perspective top view thereof;

FIG. 3 is a perspective bottom view thereof;

FIG. 4 is a front view thereof;

FIG. 5 is a rear view thereof;

FIG. 6 is a left side view thereof; and,

FIG. 7 is a right side view thereof.

The broken lines shown in the drawings illustrate portions of the jewelry that form no part of the claimed design.

1 Claim, 5 Drawing Sheets(56)
